ATTORNEY

UNITED STATES PATENT OFFICE.

JESSE RAHN, OF FLORENCE, KANSAS.

DESIGN FOR AN ARTICLE-HOLDER.

50,404.

Specification for Design.

Patented Feb. 27, 1917.

Application filed December 11, 1916. Serial No. 136,361. Term of patent 14 years.

To all whom it may concern:

Be it known that I, JESSE RAHN, a citizen of the United States, residing at Florence, in the county of Marion and State of Kansas, have invented a new, original, and ornamental Design for Article-Holders, of which the following is a specification, reference being had to the accompanying drawing, forming a part thereof.

The figure is a perspective view of an article holder, showing my new design.

I claim:—

The ornamental design for an article holder, as shown.

JESSE RAHN.

Witnesses:

GLENN RAHN,
IRIS MILDRED RAHN.
